PAGE 2

FIG. 5.

FIG. 6.

FIG. 7.

FIG. 8.

FIG. 9.

FIG. 10.

FIGURE 1 is a front perspective view of a trailer, showing my new design;

FIGURE 2 is a rear perspective view thereof;

FIGURE 3 is a front perspective view of a modified form of the trailer shown in FIGURE 1;

FIGURE 4 is a rear perspective view thereof;

FIGURE 5 is a top plan view of the trailer shown in FIGURES 1 and 2;

FIGURE 6 is a bottom plan view of the trailer shown in FIGURES 1 and 2;

FIGURE 7 is a front perspective view of a modified form of the trailer shown in FIGURE 1;

FIGURE 8 is a rear perspective view thereof;

FIGURE 9 is a front perspective view of a modified form of the trailer shown in FIGURE 1; and

FIGURE 10 is a rear perspective view thereof.

The dominant features of my design reside in the portion shown in full lines.

This application is a continuation of applications Serial Numbers D. 73,888 and D. 73,889 filed March 8, 1963, and now abandoned.

I claim:

The ornamental design for a trailer, as shown and described.
